UNITED STATES PATENT OFFICE.

HENRY H. HANTON, OF LANCASTER, PENNSYLVANIA, ASSIGNOR TO FRAIM-SLAY-MAKER HARDWARE CO., INC., OF LANCASTER, PENNSYLVANIA, A CORPORATION OF PENNSYLVANIA.

DESIGN FOR A PADLOCK.

Application filed February 7, 1925. Serial No. 12,307. Term of patent 7 years.

To all whom it may concern:

Be it known that I, HENRY H. HANTON, a citizen of the United States, residing at Lancaster, in the county of Lancaster and State of Pennsylvania, have invented and produced a new, original, and ornamental Design for a Padlock, of which the following is a specification, reference being had to the accompanying drawings, forming a part thereof, and illustrating said design.

I regard the case as an important feature of my design.

Fig. 1 of the drawings represents a side elevation of a padlock, showing my new design; and

Fig. 2 is an end view of the same.

I claim:

The ornamental design for a padlock, as shown.

HENRY H. HANTON.
